UNITED STATES PATENT OFFICE.

WILLIAM W. COLEMAN, OF EDGEWOOD PARK, PENNSYLVANIA, ASSIGNOR
TO THE UNION SWITCH AND SIGNAL COMPANY, OF SWISSVALE,
PENNSYLVANIA, A CORPORATION OF PENNSYLVANIA.

RELAY.

No. 799,452.

Specification of Letters Patent.

Patented Sept. 12, 1905.

Application filed April 7, 1905. Serial No. 254,319.

To all whom it may concern:

Be it known that I, WILLIAM W. COLEMAN, a citizen of the United States, residing at Edgewood Park, in the county of Allegheny and

5 State of Pennsylvania, have invented certain new and useful Improvements in Relays, of which the following is a specification.

10 My invention relates to relays, and more particularly to what is known in the railway-signaling art as "interlocking relays."

An interlocking relay generally comprises two sets of magnets, each set being provided with an armature, the movement of which is used to open and close electrical circuits, and 15 an interlocking means which acts when one armature is away from its set of magnets to prevent movement of the other armature.

My invention has special reference to the interlocking means.

20 I will describe an interlocking relay embodying my invention and an application for signaling purposes and then point out the novel features thereof in claims.

In the accompanying drawings, Figure 1 is 25 an elevation of an interlocking relay embodying my invention and showing it applied to a railway to operate a crossing signal-bell. Fig. 2 is a horizontal section of the interlocking relay, taken approximately on the line $\alpha\alpha$ of Fig. 1 and looking upwardly in the direction of the arrows. Fig. 3 is an end view of Fig. 1, part of the casing being broken away. Fig. 4 is a detail view, to be referred to, showing the interlocking means in the position it 30 will assume when the magnets to the left are deenergized, due to the presence of a train in the section with which said magnets are in circuit. This view also shows the proper contacts made to close the bell-circuit for that 35 section and the armature to the right in locked position. Figs. 5 and 6 are modified detail views, to be referred to, showing the position of the parts when the magnets to right are deenergized, due to the presence of a train in 40 that section and going in an opposite direction. In this view the contacts are properly made to close the bell-circuit for that section and the armature to the left is shown as locked. Figs. 7 and 8 are diagrammatical views, the 45 former view showing two sections of a railway-track having an interlocking relay embodying my invention connected therewith, a train being shown in the section to the left

and the bell-circuit therein closed to sound an alarm, and the latter view showing the train 55 as having entered the section to the right of the crossing.

Similar reference characters indicate corresponding parts in all the figures of the drawings.

R designates an interlocking relay embodying my invention, which, as previously mentioned, generally comprises two sets of magnets, as also various binding-posts and other parts common to such class of instruments 65 and so well known to those skilled in the art as not to need any lengthy or specific description. The magnets are arranged in pairs and are designated, respectively, r and r' , being secured to a suitable table or plate 1, 70 which corresponds in point of contour with a base-plate 2, both of which are separated from each other to form a convenient box or compartment 3 for the various operating and other parts by means of the transparent plates 75 4, preferably glass, the ends of which are usually retained in keepers 5, while the upper and lower edges thereof bear against the contiguous faces of the table or plate 1 and the base-plate 2, the whole being secured together 80 by suitable screw-bolts 6.

The cores of the respective magnets r and r' project through the table or plate 1, and the upper extremities of each pair are bridged by the usual pole-pieces 7 and 8, respectively, their lower extremities being preferably provided each with an enlarged pole-piece 7^a and 8^a, which constitute the N and S poles of the magnets and which under the influence of current in said magnets serve to 90 give a strong pull to the armatures 9 and 10, pivotally supported by and located in proper relation with said pole-pieces 7^a and 8^a, as shown. Each of the armatures has secured to it in any suitable manner an arm 11 12 and 95 the outer free ends thereof, which are arranged to extend downwardly and toward each other and which are preferably provided with shoulders 11^a and 12^a, respectively, are engaged and locked by an interlocking 100 means 13 when the latter is moved to one side or the other, due to the change of position of the respective armatures, as I shall presently describe.

The interlocking means is conveniently located with relation to the armatures and, as

shown in Figs. 1 to 5, inclusive, may take the form of a swinging member 13, movably mounted upon a pivot 14 and adapted to engage the depending arms 11 and 12, so that upon the 5 release of one armature by one set of magnets said interlocking means will be moved to engage and lock the armature of the other pair of magnets, or, as shown in Fig. 6, the interlocking means may comprise a rigid member 13^a, arranged in the path of movement of the depending arms 11 and 12 and so disposed relatively therewith as to also lock and prevent the movement of one armature while the other armature is in unlocked or released 10 position. I will describe each of these interlocking means separately, premising that their operation is essentially alike in each instance.

In Figs. 1 to 4, inclusive, the interlocking 20 means takes the form of a bell-crank or escapement lever 13, pivotally supported in a fixed bearing 15, and is normally held so that its respective arms will lie in a horizontal or approximately horizontal position, as shown 25 in Fig. 1, with its terminals resting one on each of the bent arms 11 and 12, which, as previously mentioned, are secured to the armatures 9 and 10. Now the position of the armatures with respect to their coacting magnets is such that they are free to move slightly 30 away from their poles without closing the bell-circuits, as I shall presently describe, either while under or not under the influence of electric current. When the parts are in 35 the position shown in Fig. 4, the magnets to the left are deenergized, and their armature 9 in falling away will lift the free end of the bent arm 11, thereby moving that arm of the bell-crank or escapement lever 13 which rests 40 upon it, so as to bring its opposite arm beyond a shoulder 12^a on the opposite bent arm 12; but under conditions where the other set of magnets to the right are deenergized simultaneously therewith or immediately after the 45 armature 10 in falling away therefrom will engage the other arm of the interlocking means, thereby limiting its movement, and so preventing the closing of the circuit. The weight of the armature will serve to maintain 50 the interlocking means in this position, and the shoulder 11^a or 12^a, as the case may be, will prevent disturbance of the interlocking means until such time as the magnets r' are again energized and the armature 10 attracted 55 to the core thereof, which will effect the lifting of its weight from the interlocking means, and thus permit it to assume its initial position, as shown in Figs. 1 and 8. Gravity alone may suffice to bring the interlocking means 60 back into such position; but I prefer to employ means for positively accomplishing this return movement. This means may, as shown, comprise a spring 16, one end of which is connected with the bell-crank or escapement lever 13, the other end being secured to the

plate or table 1. Thus when the parts are as shown in Fig. 4 a tension will be exerted on the spring 16 sufficiently to bring the bell-crank or escapement lever 13 back to its initial position immediately after it has been 70 released from the weight of the armature 9 or 10 of that particular arm 11 or 12 with which it may at the time be engaged. 17 and 18 designate, respectively, two sets of contact-bars supported by and properly insulated 75 from the armatures 9 and 10 and adapted to move therewith. These bars are preferably arranged one on each side of each of the bent arms 11 and 12 and are provided at their inner extremities with contact fingers or plates 17^a 17^b and 18^a 18^b, adapted to engage appropriate front and back contacts in the ordinary manner, and so make and break certain circuits during the presence in or absence of current from the respective magnets r' r'. 80 The opposite ends of these contact-bars are preferably provided with flexible or yielding strips or conductors 19 20, which connect with binding-posts 21 22, which in turn may connect with an appropriate crossing signal-bell 85 B or other part or appliance, through the medium of wires 23 24, in the usual manner. The front contacts (herein designated by the numerals 25 26) extend upwardly through the table or plate 1 and terminate in binding-posts 90 27 28, the latter being connected to each other by wires 29 30, and which in turn are connected to a wire 31, leading to one pole of a battery B', employed for supplying current to the alarm or signal bell B or other part or 95 appliance to be operated. To the opposite pole of the battery B' is connected a wire 33, which completes the circuit for the alarm or other part or appliance to be operated. 100 In Fig. 5 the interlocking means 13 is shown 105 as comprising a pivotal member having its lower extremity provided with teeth t t', located one at each side of a reduced extension t² and adapted to alternately enter depressions provided in the ends of the bent arms 11 and 12. When this construction of my invention is applied to railway-signals and the parts are in the position shown, a train may be presumed to be within the track-section to the right, and the magnets r' for that section 110 are consequently deenergized. The coacting armature 10 will thereupon fall, lifting the free end of the bent arm 12 into contact with the outer edge of the tooth t', moving the locking member 13 to the left, so as to bring 115 its tooth t into register with the depression in the bent arm 11 at the opposite side of the extension t², where they will engage each other, and so lock the armature 9 against falling when its coacting magnets are deenergized 120 by the presence of a train in the section with which they are in circuit. The train on leaving the section to the right causes the battery X to energize the magnets in that section, thereby attracting the armature 10 and caus- 125 130

ing the bent arm 12 to assume the position shown in dotted lines. When now the train has passed into the section to the left, the magnets in that section, of course, will be de- 5 energized; but their armature, as first described, is prevented from falling and closing the circuit for the bell or other part or appliance. The train having passed out of this section and into the next succeeding one, 10 leaves a battery X, which is included in a track-circuit for the block-section to the left, free to energize the magnets r , with which it is in circuit, thus attracting the armature 9 and lowering the end of the bent arm 11 suffi- 15 ciently to bring the depression therein away from the tooth t , and thus permitting the locking member 13 to swing to the perpendicular position, ready to be moved to one side or the other, due to the energizing or de- 20 energizing of the respective magnets r r' , as the case may be.

In Fig. 6, which illustrates a slightly-modified form of my invention, the interlocking means is shown as comprising a stationary 25 member 13^a, secured to the table or plate 1 and against which the lower extremities of the bent arms 11 and 12 will alternately strike when the respective magnets are deenergized, as previously described. In this construction 30 the lower end of the interlocking means is provided with a threaded socket to receive the threaded end of a rod or pintle 13^b, by which means it will be apparent that accurate adjustment may be given to suit the movement 35 of the respective armatures. A binding-nut 13^c may be provided, as shown, for locking the rod or pintle 13^b after proper adjustment thereof. In the operation of this form of interlocking means the same results 40 as those previously described are effected—namely, the movement of one armature, owing to the deenergization of its magnets, serves to prevent the operation of the opposing armature even though its magnets may 45 also be deenergized. When this construction of my invention is applied to a railway-signal, the bent arm 11 will contact with the end of the rod or pintle 13^b of the interlocking means, due to the presence of a train 50 in the track-section with which its magnets are in circuit, and the opposing arm 12 is held away from contact therewith owing to the armature 10 being attracted by its magnets. The ends of these arms 11 and 12 are 55 preferably provided with hooks 11^a and 12^a, respectively, so that when a train passes from one section into the other and while yet a portion of such train is in both sections it will be apparent that both magnets will be de- 60 energized, thus lifting the arm 12 until its hook will interlock with or pass under the hooked end of the opposing arm 11, in which position they will remain until the train has cleared both track-sections. The movement 65 of one arm is limited by contacting with the

end of the other or opposing arm, so that the contacts (not shown) in moving therewith will not engage the poles in the circuit, thus preventing the closing thereof. In this form of my invention when the magnets are again 70 energized and their respective armatures attracted the interlocking ends of the bent arms 11 and 12 will be released, whereupon they will assume their normal position—i. e., the terminals of both arms will lie in a practically horizontally plane and assume the position of the arm 12 to the right.

Suitable track-batteries X X', respectively, are of course provided as a source of current-supply for each track-circuit, and the wires 80 34 35 lead from the track-section to the left to the windings of the magnets r , while similar wires 36 37 lead from the track-section to the right to the windings of the magnets r' .

Having thus described my invention, what 85 I claim, and desire to secure by Letters Patent, is—

1. An interlocking relay, comprising electromagnets and coacting armatures, and an interlocking means operable upon the movement 90 of the armature of one of the electromagnets to lock the armature of the other electromagnet.

2. An interlocking relay, comprising two sets of electromagnets and coacting armatures, 95 and an interlocking means operable upon the movement of the armature of one set of the electromagnets to lock the armature of the other set of electromagnets.

3. An interlocking relay, comprising two 100 sets of electromagnets and coacting armatures having extensions thereon, and an interlocking means operable upon the movement of the armature of one set of magnets to engage the extension on and lock the armature of the 105 other set of electromagnets.

4. An interlocking relay, comprising electromagnets and coacting armatures, interlocking means operable upon the movement of one armature to effect the locking of the other 110 armature, and means for returning said interlocking means to its normal or initial position.

5. An interlocking relay, comprising electromagnets and coacting armatures, and an interlocking means coacting with and disposed in the path of movement of said armatures whereby upon the operation of one armature said interlocking means effects the locking of the other armature. 115

6. An interlocking relay for controlling the 120 operation of railway-signals comprising electromagnets and coacting armatures, and an interlocking means comprising a member arranged in the path of movement of said armatures and adapted to lock one of said armatures coincidentally with the release of the other due to the presence in or absence of current from the respective magnets. 125

7. The combination with a railway-signal 130 of the character described, comprising a de-

vice for giving an alarm or warning on the approach of a train toward a grade or other crossing, of an interlocking relay, comprising electromagnets and coacting armatures in circuit with said signal device and with the track-sections, a source of current-supply therefor, and an interlocking means operable upon the movement of the armature of one of the electromagnets to lock the armature of the other electromagnet.

8. The combination with a railway-signal of the character just described, comprising an electrical device for giving an alarm or warning on the approach of a train toward a grade or other crossing, in either direction, a source of current-supply therefor, of an interlocking relay, comprising electromagnets and coacting armatures in circuit with said signal device and with the track-sections, a source of current-supply therefor, and an interlocking means operable upon the movement of the armature of one of the electromagnets to lock the armature of the other electromagnet.

9. The combination with a railway-signal of the character described, comprising a device for giving an alarm or warning on the approach of a train toward a grade or other crossing, a source of electric-current supply therefor, of an interlocking relay, comprising two sets of electromagnets and coacting armatures in circuit with said signal device and with the track-sections insulated from each other and located at either side of the crossing, a source of current-supply therefor, and an interlocking means operable upon the movement of the armature of one set of magnets to engage the extension on and lock the armature of the other set of electromagnets.

10. The combination with a railway-signal of the character described, comprising an electrical device for giving an alarm-warning on the approach of a train toward a grade or other crossing, a source of current-supply therefor, of an interlocking relay, comprising electromagnets and coacting armatures in circuit with said signal device and with track-sections insulated from each other and located at opposite sides of the crossing, interlocking means operable upon the movement of one armature to effect the locking of the other armature, and means for returning said interlocking means to its normal or initial position.

11. The combination with a railway-signal of the character described, comprising a signal-bell adapted to give warning on the approach of a train toward a grade or other crossing, in

either direction, a source of current-supply therefor, and an interlocking relay comprising electromagnets and coacting armatures in circuit with said signal-bell and with track-sections insulated from each other and located at opposite sides of the crossing, and an interlocking means coacting with and disposed in the path of movement of said armatures whereby upon the operation of one armature said interlocking means effects the locking of the other armature.

12. An interlocking relay comprising two sets of electromagnets and coacting armatures, a pivotal member adapted to normally engage said armatures during the presence of current in the magnets and adapted to move upon the deenergization of one set of magnets and lock the armature of the other set of magnets.

13. An interlocking relay comprising two sets of electromagnets and coacting armatures, a pivotal member adapted to normally engage said armatures during the presence of current in the magnets and adapted to move upon the deenergization of one set of magnets and lock the armature of the other set of magnets, and a spring engaging said pivotal member for returning it to its initial position.

14. An interlocking relay comprising two sets of electromagnets and coacting armatures, the latter having extensions thereon and being provided with shoulders or catches at their terminals, a locking member arranged in the path of movement of said armatures and adapted to alternately engage the shoulders or catches on the extensions and lock the respective armatures during the absence of current in the respective magnets.

15. An interlocking relay comprising two sets of electromagnets and coacting armatures, the latter having extensions thereon and being provided with shoulders or catches at their terminals, a bell-crank or escapement lever, the terminals of which are adapted to normally rest upon the extensions on the respective armatures and being operable upon the deenergizing of one set of magnets to lock the armature of the other set of magnets, and a spring engaging said bell-crank or escapement lever for returning it to its normal or initial position.

In testimony whereof I have signed my name to this specification in the presence of two subscribing witnesses.

WILLIAM W. COLEMAN.
